FIG. 7.

UNITED STATES PATENT OFFICE.

RULON H. DAVIS, OF SALT LAKE CITY, UTAH.

FOLDING UMBRELLA.

Application filed June 1, 1922. Serial No. 565,074.

To all whom it may concern:

Be it known that I, RULON H. DAVIS, a citizen of the United States, residing at Salt Lake City, in the county of Salt Lake and State of Utah, have invented certain new and useful Improvements in Folding Umbrellas; and I do hereby declare the following to be a full, clear, and exact description of the invention, such as will enable others skilled in the art to which it appertains to make and use the same.

This invention relates to umbrellas, parasols and kindred articles which afford protection against rain and sunshine, and has for its object to provide an article of the character aforesaid which may be folded into compact form for convenience of carrying in a satchel or other limited space.

One of the main features of the invention is the provision of a handle which also serves as a container to receive the parts when folded and reduced to compact form.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is an elevation of an umbrella embodying the invention, showing the same extended for use,

Figure 2 is a view similar to Figure 1 with the handle detached and the parts folded,

Figure 3 is a sectional detail, showing the umbrella folded and placed within the handle,

Figures 4 and 5 are detail views, showing more clearly the joint formed between the sections of the rib,

Figure 6 is a modification of the rib structure,

Figure 7 is a detail section on the line 7-7 of Figure 6,

Figure 8 is a sectional detail of the upper portion of the umbrella with the parts raised, and

Figure 9 is a detail view of a portion of the rib clamping collar.

Corresponding and like parts are referred

to in the following description and designated in the several views of the drawings by like reference characters.

The umbrella comprises a folding frame, a sectional stick and a hollow handle, the latter being of a size to receive the parts of the umbrella when folded and reduced to compact form.

The handle is designated by the numeral 1 and may be of any construction, according to the finish and cost of the article. A plug 2 closes the open end of the handle 1 and may be secured thereto in any manner and, as shown, the plug is connected to the handle by means of screw threads. The outer end of the plug 2 is recessed for a purpose presently to be explained.

The stick comprises sections 3, 4 and 5 which have a telescopic arrangement and are adapted to be held extended by any suitable means, such as spring catches 6 which may be conveniently disposed so as not to interfere with the telescoping of the sections.

The section 5 is attached to the plug 2. A retainer 7 is attached to the outer end of the section 3 and its marginal portion is flared downwardly to overhang a ring 8 to which the ribs or stretchers are pivotally attached. A thimble 9 depends from the ring 8 and is spaced a distance from the section 3 to receive the upper end of the section 4 when such sections are telescoped.

A collar 10 is mounted upon the thimble 9 and has an outer flange 11 at its upper end between which and the flared portion of the retainer 7 the inner ends of the ribs or stretchers are clamped. The flange 11 is

provided upon its upper or outer side with radial grooves 12 forming seats in which the inner ends of the ribs or stretchers are fitted.

The collar 10 has a spiral connection with the thimble 9, whereby it may be advanced to clamp the inner ends of the ribs or stretchers in the manner stated.

When the umbrella is folded, the collar 10 clears the thimble 9 and is received in the recess 2 in the outer end of the plug 2. The retainer 7 and the ring 8 are fixed to the outer end of the section 3 of the stick.

The frame of the umbrella comprises a plurality of ribs or stretchers which are pivotally connected to the ring 8, each of the ribs or stretchers comprising pivoted or

sliding sections which are adapted to be extended or folded. Each of the ribs or stretchers may comprise two or more sec-

100

105

110

tions which may be pivoted or adapted to slide, as indicated most clearly in the accompanying drawings.

Figures 4 and 5 show the rib sections *a* and *b* pivoted at *c* and held extended by a stop *d*. Figure 6 shows the rib sections *e*, *f* and *g* slidably engaged, edge portions *h* at the ends of one of the sections engaging over the edge portions of the cooperating section to retain the sections in engagement. Stops *i* limit the outward sliding of the sections.

The cover 13 is adapted to be attached centrally to the stick and to the several sections comprising the ribs or stretchers of the frame to admit of the latter folding.

When the umbrella is folded, the sections comprising the stick telescope and the frame and cover fold about the stick and are adapted to be inserted in the handle which is closed by means of the plug 2 and retains the parts in place, said plug being inverted.

What is claimed is:

1. A folding umbrella, having a collapsible stick and frame, a plug at the lower end of the stick, and a handle adapted to receive the stick and frame when collapsed, the open end of the handle being closed by said plug in either position of the parts.
2. A folding umbrella, comprising a stick, a retainer at the outer end of the stick, a ring secured to the stick adjacent the retainer and provided with a thimble, ribs having pivotal connection with the ring, and a collar loosely mounted on the thimble and having a spiral connection therewith and adapted to clamp the ribs between said retainer and itself.
3. In a folding umbrella, a stick, a re-

tainer at the outer end of the stick, a ring secured to the stick adjacent the retainer and provided with a thimble, and a collar loose on the thimble and having a flange at its upper end between which and said retainer the inner ends of the ribs are adapted to be clamped, said collar having a spiral connection with the thimble.

4. In a folding umbrella, a stick, a retainer at the outer end of the stick, a ring secured to the stick adjacent the retainer and provided with a thimble, and a collar loose on the thimble and having a flange at its upper end between which and said retainer the inner ends of the ribs are adapted to be clamped, said collar having a spiral connection with the thimble, and having radial grooves in the upper side of its flange to form seats for the reception of the inner ends of the ribs.

5. In a folding umbrella, a stick, a retainer at the outer end of the stick having its peripheral portion flared, a ring attached to the stick adjacent the retainer and provided with a thimble, ribs pivotally connected to the ring, and a collar loose on the thimble and having spiral connection therewith and provided at its upper end with an outer flange formed in its upper side with radial grooves in which the inner ends of the ribs are seated and which are clamped between the flared portion of the retainer and the flange of the collar.

In testimony whereof I affix my signature in presence of two witnesses.

RULON H. DAVIS.
